MODULATION SYSTEM

Charles A. Culver, Northfield, Minn.

Application October 14, 1931. Serial No. 568,663

1 Claim. (Cl. 179—171)

My invention pertains in general to radio signaling and specifically relates to a system for modulating high frequency energy.

One of the objects of my invention consists in providing a simple and efficient system for modulating sustained high frequency oscillations.

Another object consists in producing a modulation system in which the resistance of space discharge tube controls the output of a high frequency circuit in accordance with modulation energy.

I accomplish these and other desirable objects in a novel modulation system employing a microphone controlled space discharge tube for producing a variable resistance to effect the modulation of high frequency oscillations.

In the drawing which accompanies and forms a part of this specification and in which like reference numerals designate corresponding parts throughout:

Fig. 1 is a diagrammatic representation of one embodiment of the modulation system of my invention; and

Fig. 2 is a diagrammatic representation of an alternative form of the circuit arrangements of the system of Fig. 1.

My invention contemplates providing a modulation system in which modulation energy impressed between the cathode and anode of a space discharge tube varies the internal resistance of the space discharge tube for controlling a high frequency circuit. In accordance with my invention, a space discharge tube is employed as a variable resistance to control the amplitude of high frequency oscillations fed into a high frequency amplifier tube.

Referring to the drawing in detail, and specifically to Fig. 1, there is provided a source of high frequency oscillations 1 connected between the grid and cathode of a space discharge amplifier tube 2 having a source of biasing voltage 3. The output or anode to cathode circuit of the space discharge tube 2 includes an inductance 6 and a source of anode voltage 4. The condenser 5 is connected in parallel with the inductance 6.

A connection is provided from inductance 6 through the condenser 7 to the grid of a space discharge amplifier tube 8. A connection is also provided from the cathode of space discharge tube 8 to the inductance 6. A source of biasing voltage 9 is connected, as shown, between the cathode and grid of the space discharge tube 8. The output or anode to cathode circuit of space discharge tube 8 includes a condenser 11 and an inductance 10 electro-magnetically coupled

to an inductance 12. A condenser 13 is connected in parallel with the inductance 10. A source of anode voltage 14 is provided in circuit with the anode and cathode of space discharge tube 8, as shown. The inductance 12 is connected with a load 16 which is indicative of any work circuit for the utilization of modulated high frequency oscillations, such as an antenna system.

In accordance with the system of my invention, a space discharge tube 18 is provided having the anode and cathode thereof connected across the inductance 6 whereby the space discharge tube 18 serves as a resistance in shunt with the inductance 6. A microphone 19 is connected in series with a source of voltage 20 and inductance 21, which circuit is indicative of any source of modulation energy. The inductance 21 forms the primary of an audio frequency transformer having the secondary winding thereof connected between the grid and cathode of space discharge tube 18. A source of biasing voltage 22 is connected in series with the winding 23 as shown.

In the operation of my system for producing modulated high frequency oscillations, the source 1 produces high frequency oscillations which are amplified by the amplifier tube 2. These high frequency oscillations traverse the inductance 6 and are directed through condenser 7 to the grid of space discharge tube 8. The circuit 19—20—21 induces voltages in the winding 23 which control the internal, or anode to cathode resistance of the space discharge tube 18 in accordance with the modulation energy under control of the microphone 19. This variation of the resistance of space discharge tube 18 acts as a variable resistance in shunt with inductance 6 for controlling the amplitude of the high frequency oscillations impressed upon space discharge tube 8. The amplified high frequency oscillations available to the load 16 will therefore be modulated in accordance with modulation energy under control of microphone 19.

Fig. 2 is an alternative arrangement of the circuit of Fig. 1. Referring to Fig. 2, the inductance 6 is electro-magnetically coupled to an inductance 15 connected between the grid and cathode of space discharge tube 8. The output or anode to cathode circuit of the space discharge tube 18 then includes inductance 15 whereby the space discharge tube 18 serves as a variable resistance in shunt with the inductance 15, as before. Other circuit components shown in Fig. 2, as well as their operation, are substantially similar to Fig. 1. Although Fig. 2 shows an alternative of the circuit arrangement of

Fig. 1, it will, of course, be understood that various other modifications can be made without departing from the intended scope of my invention. For example, the anode and cathode connections 5 of space discharge tube 18 with reference to the space discharge tube 8 might be reversed.

It will now be evident that I have provided a novel form of modulation system which I have found in experiments produces faithful modulation and which offers many advantages in its use. One of the chief advantages accruing from my system resides in that the use of a modulation choke, or the use of any iron or other magnetic material is avoided, whereby the fidelity 10 of modulation is greatly improved. Although I have shown a preferred embodiment of my modulation system I do not desire to be limited thereto except insofar as may be pointed out in the appended claim.

20 What I claim as new and original and desire to secure by Letters Patent of the United States is:
